Primary Examiner — Stella Reid*Assistant Examiner* — Keli L Hill(74) *Attorney, Agent, or Firm* — Klein, O'Neill & Singh, LLP(57) **CLAIM**

The ornamental design for a guitar controller, as shown and described.

DESCRIPTION

FIG. 1 is a front side perspective view of a guitar controller, embodying my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines of the figures depict environmental structure and forms no part of the claimed design.
